UNITED STATES PATENT OFFICE

FLOYD SCAFF, OF WINONA, WEST VIRGINIA

TROLLEY HANGER SWITCH

Application filed March 10, 1931. Serial No. 521,556.

This invention relates to new and useful improvements in circuit makers and breakers, and more particularly to a switch in combination with a trolley hanger.

5 The principal object of this invention is to provide a trolley hanger switch for mine locomotives, wherein the usual trolley pole will be disconnected from the locomotive motor, while the motor will be connected to 10 the usual conductor reel, when the trolley pole is resting against the hanger.

Other important objects and advantages of the invention will be found in the following specification.

15 In the drawings:—

Figure 1 represents a side elevational view of a mine locomotive, equipped with the present invention.

20 Fig. 2 represents a side elevational view of the novel hanger switch.

Fig. 3 represents a fragmentary detailed sectional view of the switch.

Fig. 4 represents a fragmentary top plan view of the hanger.

25 Fig. 5 represents an inside elevational view of one of the base blocks.

Fig. 6 represents an inside elevational view of the other base block.

Fig. 7 represents an outside elevational 30 view of the base blocks shown in Fig. 5.

Fig. 8 represents a diagrammatic view disclosing the electrical connection between the electrical devices involved.

Referring to the drawings wherein like 35 numerals designate like parts, it can be seen that numeral 5 represents the track in a mine upon which the locomotive generally referred to by numeral 6 operates.

Numeral 7 represents the usual trolley wire, 40 while numeral 8 represents the trolley pole on the locomotive 6, the same being supported by the stand 9 and provided with a contact pulley 10 at its outer end for riding engagement with the trolley wire 7. Mounted upon 45 the locomotive at one end thereof is the usual conductor reel 11 from which the conductor 12 is paid when the end of the trolley wire 7 has been reached in the mine.

Referring now in detail to the invention 50 it will be seen that the novel hanger switch

includes the base block 13, and 14. On the outer side of the base block 14 is the plate 15 secured by the bolts 16 and nuts 17. This plate 15 is provided with a pair of flanges 18—18 between which the lever 19 is rockably mounted on the pin 20. A contact 21 on the lower end of the lever 19 is opposite the contact 22 from the lower end of the block 14.

55 The contact 21 is provided with a binding post 23, while the contact 22 is provided with a binding post 24. At a point above the pivot pin 20 is the contact 25 opposite the contact 26 on the upper end of the block 14. The contact 26 has a binding post 27. The contact 25 has a binding post 28 and the binding posts 23 and 28 are connected by the jumper 29. A coiled spring 30 is interposed between the rod 14 and the lever 19 to normally maintain the contacts 21 and 22 engaged when the trolley pole 8 has its roller 70 10 engaging the wire 7.

60 As can be clearly seen in Figs. 2 and 4, the upper end of the lever 19 is provided with a laterally disposed extension 31 upon which the hook 32 is pivotally mounted on a horizontal plane as at 33. The inner end of the hook 32 is provided with a lug 34 and the upper end of the lever 19 is also provided with a lug 35.

65 Interposed between these 34 and 35 is the coiled spring 36. This coiled spring serves to maintain the hook 32 substantially aligned with the extension 31. However, in the event the hook strikes against something, it will readily give, and thus no damage can be incurred.

70 As is shown in Fig. 6, the inner side of the block 13 is provided with recesses 37—37 for accommodating the posts 24 and 27, while interposed between these recesses 37—37 are the recesses 38—38 for accommodating the nuts 17—17.

75 Referring now to the diagrammatic view of Fig. 8 it can be seen that with the trolley pole in use, current flows from the trolley wire 7 through the pole 8 through the conductor 39. This conductor 39 is connected to the binding post 24. Due to the engagement of the contacts 21 and 22, when the pole is disengaged from the hook 32, the current 80 100

will flow through the aforementioned jumper 29 to the conductor 40.

Through the conductor 40, the current flows to the contactor 41 of the controller generally referred to by numeral 42. Connected to the controller 42 is the wire 43 which extends to the motor 44 of the locomotive.

As is usual in mines, when the end of the trolley wire 7 is reached, the trolley pole 8 must be lowered and the reel conductor 12 is clipped to the trolley wire 7 as at 45. Now with the pole 8 engaging under the hook 32, the spring 30 will be overcome, so that the contacts 25 and 26 are engaging.

Thus the current flows from the wire 7 through the conductor 12 to the contact 26 thru the contact 25, to the wire 40 and obviously through this wire and controller to the motor 44.

While the contacts 25 and 26 are engaging, the contacts 21 and 22 are disengaged, so that there is no current on the conductor 39.

It is thought that the construction and operation as herein given is sufficient to permit one skilled in this particular art to readily understand and reproduce the same.

While the foregoing specification sets forth the invention in specific terms, it is to be understood that numerous changes in the shape, size and materials may be resorted to without departing from the spirit and scope of the invention as claimed hereinafter.

Having thus described my invention, what I claim as new is:—

35 1. A hanger switch comprising a base, a rockable lever on the base, a hook on the lever for engagement with an object, a pair of contacts on the lever at opposite sides of the fulcrum point thereof, a pair of contacts on the base, opposed to the contacts on the lever, and spring means interposed between the lever and the base for normally maintaining one set engaged while the other is disengaged.

40 2. A trolley pole hanger comprising an arm, a hook pivotally mounted on the arm, and spring means between the arm and the hook for normally maintaining the hook in the proper position for receiving a trolley pole.

45 In testimony whereof I affix my signature.
50 FLOYD SCAFF.
